United States Patent Office.

WILLIAM H. TOWERS, OF BOSTON, MASSACHUSETTS.

Letters Patent No. 88,824, dated April 13, 1869.

IMPROVEMENT IN BOOTS AND SHOES.

The Schedule referred to in these Letters Patent and making part of the same.

To all to whom these presents shall come:

Be it known that I, WILLIAM H. TOWERS, of Boston, in the county of Suffolk, and State of Massachusetts, have made an invention of a new and useful Improvement in the Manufacture of Boots and Shoes; and do hereby declare the following to be a full, clear, and exact description thereof, due reference being had to the accompanying drawings, making part of this specification, and in which—

Figure 1 is a vertical and longitudinal section, and

Figure 2, a vertical and transverse section of a lady's cloth boot, embodying my invention or improvement.

The invention comprising the subject-matter of these Letters Patent relates to means for insuring perfect protection for the feet of a person against external moisture, by providing a boot or shoe with a water-proof lining, which shall cover the sole, and partially or wholly envelop the foot of the wearer, and form an impervious casing for the same.

This invention, which is mainly intended for application to cloth boots, consists, primarily, in forming the lining of a boot, or some classes of shoes, of a water-proof material; and secondly, in continuing such lining beyond the lower edges or outlines of the upper, and in overlapping such excess of the lining upon the outer or under surface of the inner sole, by this means creating a continuous impervious covering to the entire foot, or a greater portion thereof.

In the drawings before mentioned, as accompanying this specification, and which illustrate my invention, A denotes a lady's cloth boot, of which B is the upper, or body, and C, the sole, the lining being shown at D, such parts being made and combined in the usual manner with the exception of the lining.

In carrying out my invention, I enlarge the lining, and extend it beyond the lower edges of the upper, and I overlap such extended edges *a* of the lining upon the under surface of the inner sole *b*, and so as to entirely cover such inner sole from end to end thereof, by this means providing a joint which moisture cannot pass to reach the foot.

The edges of the lining should lap sufficiently to pre-

sent an impervious barrier to the passage of moisture at or near the edges of the inner sole. This, however, is a matter of degree, and in nowise limiting or affecting the character of my invention, the main condition of which consists in producing a continuous impervious covering for the whole or a major portion of the foot, including the sole, and from thence upward.

The lining D, formed and applied as described, is to be composed preferably of a textile fabric, treated by a material or composition impervious to moisture.

I am aware that previous to my present invention, various water-proof inner soles have been made which protect only the bottom of the foot of the wearer, but do not prevent ingress of moisture to the interior of the boot.

I am also aware that a cord, composed of a water-proof material, has been sewed into the seams which unite the sole and upper of a boot.

So far as my knowledge extends, however, nothing has been done heretofore which provides a continuous impervious covering to the entire foot, or a greater portion thereof, as accomplished by my invention.

A boot, made as contemplated by my invention, possesses the advantage of being impervious to external moisture, without the disagreeable sensations and consequences resulting from the use of India rubber, as at present.

Claims.

I claim as my invention, and desire to secure by Letters Patent of the United States—

1. Providing a boot or shoe with an entire water-proof or impervious lining, applied so as to underlap between the inner and outer soles, and avoid a seam at or near the joining of the sole and upper of the boot or shoe, substantially as set forth.

2. A boot or shoe, made with a continuous lining, so as to envelop the body of the foot, substantially as described.

WM. H. TOWERS.
